UNITED STATES PATENT OFFICE.

LEWIS H. FENNELL, OF GREENSBURG, PENNSYLVANIA.

CHAIR.

Application filed September 13, 1922. Serial No. 588,052.

To all whom it may concern:

Be it known that I, LEWIS H. FENNELL, a citizen of the United States, and resident of Greensburg, in the county of Westmoreland and State of Pennsylvania, have invented a new and useful Improvement in Chairs; and I do hereby declare the following to be a full, clear, and exact description thereof.

10 My invention relates to chairs for household use, and its object is to provide such a chair with an auxiliary seat device for small children, such auxiliary device forming a permanent and inconspicuous part of 15 the chair, and being easily and quickly adjustable to various heights.

In the accompanying drawing, Fig. 1 is a perspective view of a chair constructed in accordance with my invention; Fig. 2 is 20 an enlarged vertical sectional view showing the auxiliary seat in its upper operative position; Fig. 3 is a vertical sectional view showing the auxiliary seat adjusted to its lower operative position; Fig. 4 is a 25 fragmentary vertical section showing the manner in which the auxiliary seat is folded when not in use; Fig. 5 is an enlarged side view of one of the plates which guide and support the rear of the auxiliary seat; and 30 Fig. 6 is a perspective view of one corner of the auxiliary seat showing one method of attaching a supporting pin thereto.

The drawing shows a chair having the usual seat 2 and legs 3 and the usual back 35 consisting of side rails 4 and a panel 5. These parts may be of any usual or desired construction.

Secured to the inner side of each of the rails 4 is a guide plate 6 having a slot 7 40 and a recess 8 communicating with the slot 7. The plates 6 may be attached to the side rails 4 by means of screws 9 or otherwise, and the slots serve as guides for an auxiliary seat 10 having pins 11 projecting 45 from its rear corners and received in the slots 7 of the plates 6. Figure 6 of the drawing shows one method of attaching the pins 11 to the auxiliary seat 10, such means consisting of a small plate 12 screwed or 50 otherwise attached to the under side of the seat 10 and having an ear 13 which carries the pin 11.

The seat 10 is provided near its front edge with a supporting member 15 which is 55 attached to the under side of the seat 10 by means of hinges 16. The swinging edge

of the supporting member 15 may be provided with a strip 17 of felt or other suitable material to prevent the edge of the supporting member from scratching or bruising the chair seat.

Some chairs have horizontal rails, such as the rail 18 shown on the drawing, extending between the side rails and projecting above the chair seat. If the chair to be 65 equipped with my auxiliary seat does not have such a rail the rail 18 is added, as shown on the drawing, and may suitably be provided with a groove 19 in its upper surface to receive the edge 20 of the auxiliary 70 seat 10 when the auxiliary seat is folded into the position shown in Fig. 4. The rail 18 serves as an abutment against which the lower edge of the supporting member 15 rests when the auxiliary seat is adjusted in 75 its lower operative position, as shown in Fig. 3.

Suitable means, such as a hook 22 and a screw eye 23, may be provided for securing the supporting member 15 in its folded position, as shown in Fig. 4.

When the auxiliary seat is not required, the supporting member is folded beneath the seat member 10 and the entire device is moved to the position shown in Fig. 4 where it forms a part of the chair back and presents a neat and inconspicuous appearance. The chair is then suitable for any ordinary use according to its design. It will usually be a dining chair or a kitchen chair, but the 90 use of my device is obviously not restricted to these particular kinds of chairs.

While the auxiliary seat device is thus out of the way and almost unnoticeable, it is ready at a moment's notice to be converted 95 into a high chair for small children, and when so used may be adjusted either for the height shown in Fig. 2, in which case the pins 11 are received in the recesses 8 of the guide plate 6, or for the lower position 100 shown in Fig. 3, in which case the pins 11 rest in the lower ends of the slots 7 and the swinging edge of the supporting member 15 rests against the rail 18. Recesses similar to the recess 8 may be provided, if desired, 105 in the lower ends of the slots 7 in order to prevent the rear edge of the auxiliary seat from being tilted up if the weight of the child should rest upon the front edge of the auxiliary seat.

This device, without materially changing the appearance of an ordinary chair, is a

convenience when small children are to be set at a dining table, for example, and does away in such cases with the annoyance of obtaining high chairs or piling books or the like upon ordinary chairs, as is usually done. This device is also useful as a household step-ladder.

I am aware that auxiliary seat devices have been provided for chairs, but such devices have been separate constructions, in the nature of stools, to be placed on the seat of an ordinary chair, or have been hung by means of straps or hooks over the back of the chair. In either case the auxiliary device is removed from the chair and stored when not in use, and is therefore much less convenient than my present device which is a permanent part of the chair.

Various changes may be made in the construction and arrangement of parts, and it will therefore be understood that my invention is not restricted to the precise details shown in the accompanying drawing, but may be variously modified within the scope 25 of the appended claims.

I claim as my invention:

1. A chair having the usual seat and having a back comprising spaced upright rails, slotted plates secured to the inner surfaces 30 of said upright rails, an auxiliary seat having projections engaging the slots in said plates, a supporting member hinged to the said auxiliary seat near its front edge, and a transverse rail extending between said upright rails and having a groove in its upper side adapted to receive and support the lower edge of said auxiliary seat.

2. A chair having the usual seat and having a back comprising spaced upright rails, plates secured to the inner side of the said 40 upright rails and having upright slots, each provided with a lateral recess spaced above its lower end, an auxiliary seat having laterally extending pins adapted to enter said 45 slots and recesses in said plates, a supporting member hinged to the under side of said auxiliary seat near its front edge, and an abutment for engaging the lower end of said supporting member and thereby maintaining said supporting member in an in-

clined position, said supporting member being adapted, when vertical, to support said seat in horizontal alignment with said recesses, and being also adapted, when engaging said abutment, to support said auxiliary 55 seat in horizontal position in alignment with the lower ends of said slots.

3. A chair having the usual seat and having a back comprising spaced upright rails, plates secured to the inner side of the said 60 upright rails and having upright slots, each provided with a lateral recess spaced above its lower end, an auxiliary seat having laterally extending pins adapted to enter said slots and recesses in said plates, a supporting 65 member hinged to the underside of said auxiliary seat near its front edge, and a transverse rail extending between the said upright rails and adapted to form an abutment for the lower edge of said supporting 70 member, said supporting member being adapted, when vertical, to support said seat in horizontal alignment with said recesses, and being also adapted to rest against said rail and to support the said auxiliary seat 75 in horizontal position in alignment with the lower ends of said slots.

4. A chair having the usual seat and a back comprising upright side rails, plates secured to the inner sides of said rails, and having slots extending in a generally vertical direction and recesses extending rearwardly and downwardly from said slots between the ends of said slots, a horizontal rail extending between said upright rails adjacent to the 85 chair seat, an auxiliary seat having laterally extending pins received in said slots and adapted to enter said recesses, and a supporting member hinged to the under side of said auxiliary seat and adapted, when vertical, to support said seat in horizontal alignment with said recesses, the said supporting member being also adapted to rest against the said rail and to support the said auxiliary seat in horizontal position in 95 alignment with the lower ends of said slots.

In testimony whereof I, the said LEWIS H. FENNELL, have hereunto set my hand.

LEWIS H. FENNELL.
